UNITED STATES PATENT OFFICE.

GEORGE F. A. McDougall, of Dorchester, Massachusetts.

AEROPLANE.

1,002,724.

Specification of Letters Patent. Patented Sept. 5, 1911.

Application filed September 20, 1910. Serial No. 582,907.

To all whom it may concern:

Be it known that I, GEORGE F. A. McDougall, a citizen of the United States, residing at Dorchester, in the county of Suffolk and State of Massachusetts, have invented certain new and useful Improvements in Aeroplanes, of which the following is a specification, reference being had therein to the accompanying drawings.

10 My invention relates to improvements in aeroplanes of that type known as monoplanes and resembling somewhat the form of a bird.

15 The object of my invention is the providing of an aeroplane so constructed as to allow of a much quicker getaway; which will have much greater speed; which can also be propelled through the air very slowly; and which will have great air 20 climbing power.

25 A still further object is the construction of an aeroplane which will turn in extremely small circles without the tilting of the body of the machine as is now necessary, with the well known types of aeroplanes.

With these objects in view, this invention consists in certain novel features of construction, and in certain parts, improvements, and combinations as will be herein- 30 after fully described in this specification and set forth in the claims.

In the accompanying drawings, Figure 1 is a plan view of my invention with part of the hood plane broken away to better illustrate the motors and adjacent parts. Fig. 2 is a side elevation of the same. Fig. 3 is a front elevation of the same, the rear portion of the machine being omitted for the purpose of illustration and clearness. Fig. 40 4 is a perspective view of the rudder.

45 Corresponding and like parts are referred to in the following description and indicated in all the views of the drawings by the same reference characters.

Referring to the drawings, the floor 1 of the chassis which supports the engines or motors 2 and 3 is constructed of any light but strong material and is situated beneath the plane of the main plane 4 and the inner 50 sides of the wing planes 5 and 6, extending from points beneath the inner sides of the wing planes and between the points 7 8. This chassis would also contain the seat (not shown) of the aviator, and supports the frame-work 9 on which the starting wheels 10 are mounted. It is apparent that skids

could be substituted for these wheels or that they could be used in addition to the wheels for relieving the wheels of considerable shock, and that heavy timbers for supporting the engines could be substituted for the chassis.

The frame-work 12 is supported from the chassis and fore and aft of the same, also extending upward from the four corners of the chassis with proper cross-bars, as for example, cross bars 24 through which the shaft 26 extends and has bearings. The upper part 13 of the frame-work 12, above the chassis supports a semi-cylindrical hood 17, which extends forward with downwardly inclined sides 18 that extend forward to a point or nose at the top of the forward rod 14 of the frame-work 12; the forward portions of the frame-work 12 also extending forward to a point where they are connected by the rod 14, the lower portion of which supports a forward bearing 15 for the downwardly inclined driving shaft 11 of the engine 2 which drives the forward downwardly inclined propeller 16 which when the machine is running with its wheels 10 and 20 on level ground will only be slightly inclined downward. Should the aft portion of the machine rise into the air as it naturally would soon do after the propellers have been started, the incline of the forward propeller will have a tendency to raise the forward portion of the machine, and the greater the downward incline the greater the power for raising the nose of the machine.

It will be noticed that I have inclined this forward engine 2 so as to drive the propeller 16 by a direct shaft 11; also that the rear wheel 20 is of smaller diameter than the forward wheels 10 and that the vertical frame-work 19 is much shorter than the vertical frame-work 9 so that the entire body of the machine and the main plane 4 has a forward upward incline.

The main plane 4 is almost V-shaped, commencing at almost a point, just above the rear edge of the chassis, and increasing in width until its aft portion is wider than the widest portion of the chassis. The keel 21 of the machine extends downward from the central rod 22 of the frame-work 12 at a point commencing just below the forward end of the main plane to the central one of the rear rods 23 thus forming a right-angle triangular shaped keel or vertical plane.

The wing planes 5, 6 are mounted as at 27, 28 on the ends of the divided or two-part shaft 26 and are operated respectively by the hand wheels 29, 30 thereon, each 5 wing plane being operated independent of the other and locked in position by any means 31, 32. These wing planes have the strengthening ribs 25 and the camber of same depend entirely on the power of the 10 engine and size of the propellers 49 and 50, which propellers are situated under the forward portions of the wing planes, the wing planes being so constructed as to catch a portion of the air forced rearward which 15 tends to raise the forward portion or chassis part of the machine from off of the ground. Either wing plane can be tilted to catch more or less of the air forced against their under sides; by forcing down their aft part 20 a greater amount of air is caught which tends to raise the machine and by lowering the fore part the air pushed rearward by the propellers 49 or 50 will pass beneath the wing plane without having any effect 25 upon it, as in the type of a propeller such as will be used upon this machine the air will be forced rearward in columns having a diameter not much greater than that of the propeller and the air columns will not begin to increase much in diameter until they 30 have passed from beneath the wing planes. The propellers 49, 50 are mounted in bearings 55, 56 on the side arms 51, 52 and are connected with the engine 3, respectively by the sprocket chains 53, 54. If desired the machine may be started into the air with only the propeller 16 in motion or with the propellers 49, 50 in motion and the propeller 16 still. After the machine 35 has obtained the necessary height and great speed is desired, the aft end of the wing planes can be raised so that its top from front to rear will be nearly horizontal and parallel with the upper portion 13 of the 40 frame-work 12 so as to allow the air forced from the propellers 49, 50 to pass the machine without friction or retarding the machine in any degree by being forced against 45 part of it.

50 Secured to the central one of the rear rods 23 is a bar 28 terminating in a yoke 34 through which extends the bar 36 pivoted therein on the pin 35 and having the shoulders 37 above the yoke for limiting the tilting of the rudder planes 40, 41, 43, and 45, by coming in contact with the rear upper sides of the yoke on their extreme downward position and on the forward portion 55 of these upper sides on their extreme upward position in order to allow both vertical and horizontal movement of the rudder planes I construct the bar 36 with a diameter, in that portion extending through the yoke, which is less than the distance between the fingers of the yoke 34 so that the

bar 36 can be twisted or turned around on the pivot pin horizontally and in order to allow a free movement of same I enlarge the hole in the bar 36 through which the pivot pin extends enough to allow a swinging movement of this bar; the up and down positions being controlled by the wires 38, 39 which extend forward on the right hand side of the machine to the hand or control wheel 48. About midway of the bar 28 is 75 the collar 33 secured thereto from which extend the rods 27, 30, 31 and 32; the length of the combined vertical rods 27 and 30 being less than the length of the bar 36 so that the wires 38, 39 incline toward each other, 80 when taut, as they extend from the bar 36 to the rods 27, 30.

The rudder planes extend below the yoke from the bar 36, being made integral with this bar 36 and in no way connected with the yoke except through the pivot pin 35, as clearly shown in Figs. 2 and 4; the upper vertical rudder plane 40 being partly recessed at its forward portion to allow these planes to be inclined upward, as shown in 90 Fig. 2. The horizontal planes 43, 45 are controlled in horizontal movement by the wires 42, 44 which extend from near their rear edges and through the rods 31, 32 to the hand or control wheel or steering gear 47 on the left hand side of the machine; the wire 44 extending through an opening 46 in the canvas keel 21, see Fig. 2. The combined length of the two rods 31 and 32 is less than the distance from the point on the edge of 100 the rudder plane 43 where the wire 42 is attached to the point where the opposite wire 44 is attached to the rudder plane 45, so that these wires incline toward each other as they leave the rudder planes and extend toward the rods 31 and 32. The rod 36 pivoted in the yoke on the pin 35 allows the four rudder planes to be swung to the right or left, also allows the vertical rudder planes to be swung toward the horizontal, and also allows the horizontal rudder planes to be 105 swung toward the vertical.

Having thus described my invention, I claim:

1. In an aeroplane, a chassis, a horizontal main plane entirely rearward of the chassis, a keel extending downward from the main plane, rudder planes rearward of the keel and main plane, an engine, propellers on each side of the chassis driven by the engine, a secondary engine forward of the other engine, and a central forward downwardly inclined propeller driven by the secondary engine.

2. In an aeroplane, a chassis, pivoted wing planes on each side of the chassis, a horizontal flight propeller under the forward portion of each wing plane, means for driving said propellers from the chassis, means for tilting said wing planes, a main

- plane extending rearward from the chassis between the wing planes, and a hood extending over the chassis above the plane of the main plane and between the wing planes.
5. 3. In an aeroplane, a chassis, an inclined driving shaft extending below the plane of the chassis, a propeller mounted on the forward end of the driving shaft at the extreme forward portion of the aeroplane, pivoted wing planes on each side of the chassis, and propellers on each side of and in the rear of the inclined propeller, situated under the forward portions of the wing planes, mounted approximately at the same height as the highest portion of the inclined driving shaft.
4. In an aeroplane, a chassis, a keel extending rearward from the chassis the lower side of which is inclined, a flat main plane entirely rearward of the chassis covering the upper side of the keel, a rearward extending bar having a yoke shaped end, a pivot pin extending across the yoke, a bar extending through the yoke and mounted on the pivot pin, vertical and horizontal rudder planes integrally formed and secured to the pivoted bar, a steering gear, wires connecting the steering gear with the outer edges of the horizontal rudder planes, a control wheel and wires connecting the top and bottom portions of the pivoted bar with the control wheel.
5. An aeroplane comprising a chassis, wing planes pivoted on each side thereof, propellers under each wing plane, means for driving the propellers, a hood having a V-shaped forward nose, a main plane extending rearward from the chassis, a keel ex-
- tending downward from the chassis the lower edge of which is on a level with the floor of the chassis, a vertical rod extending downward from the rear portion of the main plane, a bar 28 extending rearward from the same and having a yoke at its outer end, a vertical bar extending through the yoke and pivoted therein, rudder planes rigidly mounted to the vertical pivoted bar, a collar, rods extending outward therefrom and steering means extending from the pivoted bar and horizontal rudder planes through said rods, substantially as shown and described.
6. An aeroplane consisting of a framework, wing planes, a rearward extending V-shaped main plane having its widest portion at the rear, a keel extending downward from the main plane at right angles thereto, horizontal and vertical rudder planes pivotally mounted in the rear thereof, means for turning the rudder planes in vertical and horizontal directions, horizontal flight propellers mounted on each side of the framework beneath the forward portion of each wing plane, a propeller at the extreme forward part of the machine slightly inclined downward from the horizontal, and means for operating one wing plane independent of the other wing plane, substantially as shown and described.

In testimony whereof I affix my signature in presence of two witnesses.
